UNITED STATES PATENT OFFICE.

THOMAS WESTFALL SARGENT, OF WASHINGTON, DISTRICT OF COLUMBIA.

OFFICE INDICATOR.

Application filed August 11, 1924. Serial No. 731,406.

This invention relates more particularly to an office indicator which will indicate precisely the day and hour at which a person is expected to return to his office or other place of business or dwelling.

It frequently happens that a person will be called away from his place of business for a long period of time, or he may be going on a vacation, or otherwise be absent from office. 10 It is especially for such lengthy and extended stays that my present invention is adapted and designed to indicate the expected return of a person to his place of business.

15 The invention has for its object to provide an improved office indicator of the above described type, and it consists of the features of construction hereinafter set forth in detail and succinctly defined in the appended claims, reference being had to the accompanying drawings, wherein

Figure 1 is a face view of an office indicator constructed in accordance with the present invention;

25 Figure 2 is a view of the hour indicator detached for independent use; and

Figure 3 is a detailed sectional view of one of the indicator fingers.

Referring more in detail to the accompanying drawings, the numeral 1 designates the body of my improved office indicator, which body may be stamped from sheet metal or constructed from cardboard or other suitable material. The body is divided by 30 three parallel slots 2, 3 and 4, of equal length, or substantially so, and terminating short of the marginal border 5 so as to avoid unduly weakening the structure. Above, and associated with, the slot 2 are seven spaces 6 designated respectively as the days of the week and titled "Day". Above this arrangement is left a space for appropriate design of wording, such as "Will be back". Between slots 2 and 3 are provided twelve 35 spaces 7 associated with the lower slot 3 and bearing the names of the months of the year, this series of spaces being titled "Month". Between the slots 3 and 4 are arranged thirty one spaces 8 for association with the lower slot 4 and designed to contain numerals designating the days of the month, this series of spaces being designated or titled "Date".

50 In each slot is slidably mounted an indicating finger or pointer 9, which also is preferably struck up from light metal stock and bent upon itself as depicted most clearly in

Figure 3 from which view it will be noted that both sides of the slots will be embraced by the pointer so as to steady the latter in its movements. It will also be noticed that the 50 lower side or edge of the slot will be frictionally embraced by the opposed springy portions 10 whereby the individual pointers will be firmly held or secured in their set positions.

65 The hour indicator 11 consists of a hinged leaf detachably secured to the body below the slot 4 by a removable pintle. Each face of the leaf is provided with a dial 12 having numerals designating twelve hours and being 70 equipped with hour and minute hands 13. One face of the leaf is noted "AM" and the opposite face is noted "PM". The leaf is secured to one side, or the other, by a turn button 14. When a person is to absent for a 75 few hours only, he may withdraw the pintle 15 and simply place the hour indicator on his door or desk, as desired.

The body may be secured to the door or other support by suitable fasteners passing 80 through corner apertures 16, or a suspending cord may be threaded through two or more of said apertures in an obvious manner. From the foregoing it will be noted that the particular time a person is expected to 85 return within a year may be announced on my improved indicator; that the arrangement is such that the reading may be clearly made; and that a small or auxiliary indicator may be provided for hourly indica- 90 tions when such alone are desired.

What I claim as new is:—

1. An office indicator comprising a body having a slot and indicia along one side of the slot, and a pointer operable in the body 95 slot and consisting of a strip of metal having one end portion bent upon itself to provide a reinforced back and its opposite end portion bent upon itself to provide a reinforced front and the free end of the latter 100 portion being extended to form a pointer for cooperating with the indicia on the body, the reinforced front and back frictionally embracing the body therebetween.

2. An office indicator comprising a flat 105 body having date-indicating means including a row of indicia extending across the body, means movable over the body for co-operating with the indicia of said row to indicate a predetermined day, said date indicating means being arranged so as to leave 110 a blank marginal space, an hour leaf having

- 2
- relatively complemental time indications on its opposite faces, said leaf disposed in said marginal space and hingedly connected to the body for swinging substantially parallel 5 with the row of indicia and about an axis at right angles to the row of indicia to expose either of its two faces adjacent said row one side of said hour leaf having a clock dial denoting A. M. time-indications and the op- 10posite side having a clock dial denoting P. M. time-indications, and a pair of hands for each dial movable thereover to indicate a predetermined time.
3. An office indicator comprising a flat body having slidable date-indicating means arranged so as to leave an hour space, an hour leaf hinged to the body for swinging in a plane substantially parallel to the direction of movement of said date-indicating means 15 for exposing either face within the hour space, said hour leaf having a clock dial on one side denoting A. M. time-indications and a clock dial on the opposite side denoting P. M. time-indications, hands on the opposite 20 sides of the leaf for movement over the respective dial for indicating a predetermined hour for the indicated day, said hands being connected by a common pivot, and fastening devices movably mounted on the body on op- 25posite sides of the leaf and beyond the path of movement of the free edge of said leaf for selective engagement over the leaf when the latter is swung over to lie adjacent the respective fastening device to secure the hour leaf to expose a selected one of its sides to co-operate with the date-indicating means 30 for designating a particular hour on a predetermined day.
4. An office indicator comprising a body, a predetermined date-indicating device there- 35 on, an hour-indicating device adjustably mounted on the body and consisting of a leaf having clock dials on its opposite faces, the dial on one face denoting A. M. time-indications and the dial on its opposite face denoting P. M. time-indications, said hour-indicating device being associated with said date-indicating device and adjustable to present either time-indication face for reading in conjunction with said date-indicating de- 45 vice whereby the exact hour of a remote and predetermined day may be preindicated, means for positively holding said hour-indicating device in either of its adjustable positions for exposing the corresponding time- 50 indication face thereof, and hands on the op- 55posite sides of the leaf for designating a predetermined time on the respective dial, the hand on the unexposed face being concealed and protected between the body and the leaf.
5. An office indicator comprising a flat body having date-indicating means includ- 60 ing a row of indicia extending across the body, means movable over the body for co-operating with the indicia of said row to indicate a pre-determined day, said date-indicating means being arranged so as to leave a blank marginal space, an hour leaf having relatively complemental time indications on 65 its opposite faces, said leaf disposed in said marginal space and hingedly connected to the body for swinging substantially parallel with the row of indicia and about an axis at right angles to the row of indicia to selec- 70tively expose its two faces adjacent said row, one side of said hour leaf having A. M. time-indications and the opposite side having P. M. time-indications, and an indicator for each side movable thereover to indicate a 75 predetermined time.
- In testimony whereof I affix my signature.
- THOMAS WESTFALL SARGENT.
